CONSTRUCTION OF SPINNING JETS

Cyrus O. Butler and Stephen M. Bear, Kingsport, Tenn., assignors, by mesne assignments, to Eastman Kodak Company, Jersey City, N. J., a corporation of New Jersey

Application April 12, 1935, Serial No. 16,048

3 Claims. (Cl. 18—8)

This invention relates to either dry spinning or wet spinning of artificial fibers and relates particularly to jets for use in the manufacture of artificial silk thread. One object of our invention is to provide a spinning jet which is sufficiently strong to withstand pressure on the dope from which the artificial filaments are made. Another object of our invention is to provide a spinning jet construction which permits the use of thin relatively expensive metals if necessary for the manufacture of spinning jets, and which reinforces the thin metal to withstand the necessary pressures. Another object of our invention is to provide a spinning jet of the type described in which a support is provided for a filter medium, this support offering a minimum obstruction to the dope passing through the filter and other objects will appear from the following specification, the novel features being pointed out in the claims at the end thereof.

In dry or wet spinning of artificial fibers, it is desirable to use a thin flat surfaced metallic cup so that a series of parallel orifices may be pierced through the flat cup face. It is customary to provide these orifices in a pattern and one of the best known patterns is in the form of a circle so that a series of artificial filaments can pass from the jet in a predetermined pattern and so that the filaments may be suitably twisted to form yarn. Because of the extremely small size of the orifices, the best results can be obtained with thin metal cups, a limit to the thickness of the cup being reached when the metal may become distorted or bulged outwardly due to the pressure applied to the dope in order to force it through the minute orifices. For best results, the very small orifices must be in parallel relation.

It is often necessary or desirable to filter the dope immediately before it passes into the spinning jet in order to remove any traces of foreign matter or slugs which might prevent the dope from passing freely through all of the orifices. Such a filter should have as much area exposed to the dope as possible, but since the filters may be of extremely fine wire mesh screen, or of other suitable material which is not particularly strong, it is difficult to prevent a pressure on the dope from distorting and from spoiling the operation of the filter material.

Our invention has been particularly directed to overcoming these difficulties.

Coming now to the drawing, wherein like reference characters denote like parts throughout.

Fig. 1 is a plan view of a spinning jet con-

structed in accordance with and embodying a preferred form of our invention.

Fig. 2 is a section through a spinning jet similar to that shown in Fig. 1, but with the spinning jet supported on the end of a dope supply line and with a filter in operative position.

Fig. 3 is a plan view of a spinning jet constructed in accordance with a second embodiment of our invention.

Figure 4 is a section on line 4—4 of Fig. 3. 10

Fig. 5 is a section similar to Fig. 4, but of a third embodiment of our invention.

We prefer to provide a spinning jet in the shape of a cup designated broadly as 1 having a substantially flat bottom wall 2, and upstanding side 15 wall 3 and an outwardly flared flange 4 extending around the top of the cup. The cup is provided with a series of fine perforations 5 in a predetermined pattern here shown as being in the form of a circle. This leaves the center portion 6 of the 20 cup unperforated.

We prefer to reinforce the flat unperforated bottom 6 by means of a block 7, which in accordance with Figures 1 and 2 may be welded to the bottom wall 6. The upper edge 8 of this 25 block may be provided with a series of points or projections 9 which lie substantially flush with the top edge of the cup flange 4. Thus, when a filter 10 is placed on the flange 4 it may rest on the protuberances 9 and it may also be supported 30 over the area of the flange 4 by means of the threaded ring 11 and the threaded flange 12 carried by the dope supply line 13.

From Fig. 2 it will be noted that the block 7 fills a substantial portion of the cup and also that 35 the grooves 14 in the block 7 permit dope to be forced through practically the entire area of the filter 10. Since the dope may pass through the filter into the grooves 14 and then through the grooves 14 and into the cup, the block 7 not only 40 reinforces the bottom of the cup 1, but in addition, it forms a support for the filter 10 and permits practically all of the filter to filter dope passing from the supply 13 into the spinning jet 45 to be forced through the apertures 5.

In accordance with Figs. 3 and 4, a block 17 may be provided with a series of projections 18 extending upwardly from a top 19 on the block which will be spaced from a filter supported by 50 the projections 18 and the cup flange 4. The block 17 may be attached to the cup by means of rivets 20 and if desired the bottom of the block 17 may be provided with a curved wall 21 so that the dope will be directed smoothly from the outer 55

wall of the block and the inner walls 3 of the cup to the apertures 5.

While we have found that a solid block, as shown and described in the preceding figures, is entirely satisfactory, and is particularly suitable for reinforcing the spinning jet and supporting the filter, in some cases, such as where a large spinning jet is used, it is sometimes necessary or desirable to provide a reinforcing member in the form of a block which is somewhat lighter in weight than the first described embodiments of our invention. Consequently, a cup, such as shown in Fig. 5, may be employed. In this feature, the block 27 is provided with a series of projections 28 between which there are grooves 29 as in the above described embodiments of our invention. However, the block 27 is lightened by making it hollow as indicated at 30, cutting away a large part of the material of which the block may be made. The downwardly extending annular flange 31 surrounding the hollow portion may carry a series of tapped holes 32 into which the screws 33 may pass, these screws passing through counter sunk holes in the bottom wall 6 of the spinning jet. The block may thus be held in place rigidly so as to reinforce or support the bottom wall 6 and prevent it from bulging outwardly when pressure is applied to dope passing through the jet. The function of the projections 28 are exactly the same as the functions of the projections 18 and 8 on the blocks 17 and 7 as described above.

It is possible to make still other embodiments of our invention and we contemplate as within the scope of our invention all such forms as may come within the terms of the appended claims.

Having thus described our invention, what we declare is new and desire to secure by Letters Patent of the United States is:

1. A spinning jet for producing artificial fibers and adapted to be used with a filter comprising a cup of thin metal having a plurality of apertures therein arranged in a pattern and including an outwardly extending flange at the top of the cup, the center of the cup being unperforated, a block attached to the center unperforated portion of

the cup and extending upwardly therein terminating in a top portion in substantial alignment with the flange of the cup, the top of said block including a plurality of projections with grooves in between the projections, the grooves 5 lying beneath the surface of the cup flange, the projections lying substantially in the plane of the cup flange and being adapted to form with the flange a filter support.

2. A spinning jet for producing artificial fibers 10 comprising a cup of thin metal having a plurality of apertures therein arranged in a pattern and including an outwardly extending flange at the top of the cup, the center of the cup being unperforated, a block attached to the center unperforated portion of the cup and extending upwardly therein terminating in a top portion in substantial alignment with the flange of the cup, the top of said block including a plurality of projections with grooves in between the projections, the grooves 15 lying beneath the surface of the cup flange, and a filter resting on the cup flange and on the projections from the top of the block.

3. A spinning jet for forming artificial filaments comprising a cup of thin metal of annular shape having a plurality of apertures in a flat bottom wall thereof arranged in a circle, a block attached to the unperforated portion of the bottom wall of the cup and being annular in shape, 30 said block substantially filling a material portion of the cup and leaving an annular opening between the outer wall of the block and the inner wall of the cup to which dope may be forced downwardly through the perforations in the bottom of the cup, the top of said cup including a plurality of projections and a plurality of grooves, and a filter supported by the flange of the cup and the projections of the block whereby dope may be forced downwardly through the greater 35 part of the filter and through the annular space between the block and cup and outwardly through the perforations in the bottom thereof.
